(57) **CLAIM**

The ornamental design for a brace, as shown and described.

DESCRIPTION

FIG. 1 is a front view of a brace.

FIG. 2 is a back (rear) view of the brace.

FIG. 3 is a left side view of the brace; the right side view is a mirrored image of the left side.

FIG. 4 is a floor (top) view of the brace.

FIG. 5 is a bottom view of the brace.

FIG. 6 is a perspective view of the brace.

FIG. 7 is a front perspective view of the brace in a state of use; and,

FIG. 8 is a back perspective view of the brace in a state of use.

The dot-dot-dash lines and the dashed lines in FIGS. 7 and 8 depict environmental subject matter and form no part of the claimed design. The remaining dashed lines in FIGS. 1-6 depict portions of the brace that form no part of the claimed design.

1 Claim, 5 Drawing Sheets
